US0D1078836S

(12) **United States Design Patent** (10) **Patent No.:** **US D1,078,836 S**
(45) **Date of Patent:** **** Jun. 10, 2025**

(54) **SMART GLASSES**

(71) Applicant: **Quanta Computer Inc.**, Taoyuan (TW)

(72) Inventors: **Yen-Chun Chou**, Taoyuan (TW);
Shih-Yun Lee, Taoyuan (TW);
Gwo-Chyuan Chen, Taoyuan (TW)

(73) Assignee: **QUANTA COMPUTER INC.**,
Taoyuan (TW)

(**) Term: **15 Years**

(21) Appl. No.: **29/907,293**

(22) Filed: **Jan. 5, 2024**

(30) **Foreign Application Priority Data**

Nov. 24, 2023 (TW) 112306077
